UNITED STATES PATENT OFFICE

160,956

FENDER LAMP OR SIMILAR ARTICLE

Daniel M. Pearl and Erwin M. Pearl, Chicago, Ill.

Application May 28, 1949, Serial No. 2,952

Term of patent 3½ years

(Cl. D48—32)

To all whom it may concern:

Be it known that we, Daniel M. Pearl and Erwin M. Pearl, both citizens of the United States and residents of Chicago, Cook county, Illinois, have jointly invented a new, original, and ornamental Design for a Fender Lamp or Similar Article, of which the following is a specification, reference being had to the accompanying drawing, forming a part thereof.

In the drawing:

Fig. 1 is a top plan view of a fender lamp or similar article, showing our new design.

Fig. 2 is a side elevational view of the same, the two sides being alike.

Fig. 3 is a front elevational view of the same.

Fig. 4 is a rear elevational view of the same.

The characteristic features of the design reside in the portions shown in full lines,

We claim:

The ornamental design for a fender lamp or similar article, substantially as shown and described.

DANIEL M. PEARL.
ERWIN M. PEARL.
